UNITED STATES PATENT OFFICE.

GAIUS C. FULLER, OF NEW YORK, N. Y.

FOLDING BED.

997,284.

Specification of Letters Patent. Patented July 11, 1911.

Application filed June 18, 1910. Serial No. 567,620.

To all whom it may concern:

Be it known that I, GAIUS C. FULLER, a citizen of the United States, and a resident of New York, county of New York, and 5 State of New York, have invented certain new and useful Improvements in Folding Beds, of which the following is a full, clear, and exact description.

This invention relates to folding beds and 10 particularly to metal beds, and it has for its objects the construction of a bed that shall be light and durable; simple of construction, and therefore cheap to manufacture; and which may be readily folded so that it will 15 occupy a small space.

A further object of the invention is to 20 provide means whereby the bed will be held in its extended and folded positions against accidental operation, whereby the bed will 25 be safe and reliable in operation.

A further object of the invention is to provide means whereby the mattress-supporting portion of the bed may be set and locked at any desired inclination, this feature being 25 particularly desirable in beds for use in hospitals and the like.

A further object of the invention is to so 30 construct and proportion the head and foot boards of the bed that the foot board will be smaller than the head board, and that both 35 of said boards may be of the usual standard stock sizes. The object of this is to permit beds to be made up with head and foot boards which may be obtained in the open market so that they need not be specially manufactured in order to carry out this invention.

With these and other objects in view, the 40 invention will be hereinafter more particularly described with reference to the accompanying drawings, which form a part of this specification, and will then be pointed out in the claims at the end of the description.

In the drawings, Figure 1 is a side elevation 45 of the bed in its extended position, the mattress-supporting frame being shown as inclined from the foot board downwardly toward the head board; Fig. 2 a side elevation showing a slightly modified form of 50 the bed; Fig. 3 an end elevation of the bed extended, looking at the foot board thereof; Fig. 4 a detail sectional view of one corner of the mattress-supporting frame, showing the means for holding said frame in an 55 inclined position; Fig. 5 a side elevation of the modified form of the bed illustrated in

Fig. 2, showing the bed in its folded position; Fig. 6 a detail side elevation of the means for varying the tension of the holding spring; Fig. 7 a longitudinal sectional view 60 of the device shown in Fig. 6; Fig. 8 a transverse sectional view thereof; and Fig. 9 a detail longitudinal sectional view of the holding spring compressing device shown in Fig. 1. 65

Referring to the various parts by numerals, 1 designates the mattress-supporting frame which is provided with the end pieces 2 and carries the mattress-supporting springs 3. This frame may be of any suitable construction and is preferably formed entirely of metal. 70

The head of the bed consists of the upright frame 4, to the vertical side bars of which are secured the forwardly-extending supplemental side frames 5. These side frames are only as high as the mattress-supporting frame when said frame is in its normal horizontal position. On the upper bars of these supplemental frames are secured inwardly-extending bearing lugs 6 on which are pivoted the bars 1 of the spring-supporting frame, said pivots being located a suitable distance from the adjoining end piece 2 of said frame, as shown clearly in Fig. 1. 80 85 These supplemental side frames are formed with brace rods 7 and 8 and are provided with casters 9.

The foot board 10 is of less width than the head board and is adapted to fit in between 90 the side frames 5 of the head board, when the bed is in its folded position, the relative widths of the head and the foot boards being clearly shown in Fig. 3. Secured to the vertical side bars 11 of the foot board, at 95 the lower ends thereof, are lugs 12; and to said bars at a point substantially on the level with the upper bars of the supplemental or sides frames 5 are secured lugs 13. To the lugs 12 are secured upwardly and inwardly-extending links 14, the upper inner ends of said links being connected to lugs 16 carried by the bars 1. To the lugs 13 are secured upwardly and inwardly-extending links 17, the inner ends of these links being connected to lugs 18 carried by the bars 1 of the mattress-supporting frame, the lugs 18 and 16 being located a suitable distance from each other, and the lugs 16 being located approximately midway between the end bars 2 of the mattress-supporting frame. The lugs 18 are arranged between the lugs 16 100 105 110

and the foot board of the bed so that the links 17 are considerably shorter than the links 14.

Depending from the end pieces 2 adjoining the foot board of the bed, are lugs 19 to which are connected the rear ends of cylinders 20. Pivotal connected to the links 14 a suitable distance down from their pivotal connection with the lugs 16, are cylinders 21, the rear ends of these cylinders being within the cylinders 20. Disposed within the cylinders are coil expansion springs 23 which tend to separate said cylinders and to move them longitudinally. The pivotal point between the cylinder 21 and the link 14 is so arranged that when the bed is in its full-extended position, as shown in dotted lines in Fig. 1, the cylinder 21 will be projected into the cylinder 20 to a considerable extent and the spring 23 thereby compressed. As the foot board end of the mattress-supporting frame is raised, the spring tends to expand, thereby assisting in elevating the mattress frame. After the bed has been elevated to a certain extent, the spring will have expanded to its normal position and its lifting power then ceases. In lowering the mattress frame, the two cylinders will be drawn together thereby compressing the spring and to a certain extent cushioning the action of the bed in assuming its normally extended position.

On the head board end of the mattress-supporting frame is mounted a spring latch 22 which is adapted to engage the lower rail 22^a of the foot board when the bed is in its folded position, thereby holding the bed against accidental operation, it being necessary to release said latch before the bed can be extended. This end of the mattress frame is also provided with a lug stop 22^b which is adapted to contact with the rail 22^a and to stop the mattress frame in a vertical position. If desired, the latch may be dispensed with and the lug stop alone used.

Connected to the foot board end of the mattress-supporting frame is a curved notched bar 24 which is adapted to engage the rear end of the link 17, a sliding keeper 25 being carried by said notched bar and adapted to hold the said link and the notched bar in engagement. By means of this bar, the foot board end of the mattress-supporting frame may be held at any desired elevation. This is desirable, particularly in cots and beds used in hospitals.

Referring to the construction shown in Figs. 2 and 5, the links 14^a have connected to them bars 21^a entering the side frames 1^a of the mattress-supporting frame, said bars 21^a being connected to a socket piece 26 slidably in said frame, one end of said socket piece being connected to a holding spring 23^a. The operation of this bar 21^a and

spring 23^a is precisely the same as the spring 23 in assisting in raising the foot board end of the mattress frame. One end of the spring 23^a is rigidly connected to a part of the side bar 1^a, as shown clearly in Fig. 5. 76

The socket piece 26 is formed with the openings 27 and the cross pieces 28 at intervals there-along in order that the bar 21^a may be projected through any one of said openings and engaged with the registering cross-bar in order to vary the tension of the holding spring. 75

In the form of head board illustrated in Figs. 2 and 5, the side bar 1^a is provided with a leg 29 carrying a caster 30 at its lower end and the head board proper is provided with a caster 30^a which normally extends rearwardly from the head board. In this construction, the head board is rigidly connected to the side bar 1^a of the mattress-supporting frame, and the lower end of the head board is connected to the lower end of the leg 29 by means of a curved runner or rocker 31. It is, therefore, clear that in moving the mattress frame to a vertical position, the said frame and the head board will rock on the runner or rocker 31 until the caster 30^a bears on the floor or other support, so that the said caster 30^a supports the bed in its folded position 95 while the caster 30 supports the bed in its extended or lowered position. The upper portion 32 of the head board is hinged to the lower rigid part 33 thereof so that when the bed is in its upright or folded 100 position, said upper hinged portion of the head board may be folded into a folded position parallel with the mattress-supporting frame, as shown clearly in Fig. 5.

Having thus described my invention, I 105 claim as new and desire to secure by Letters Patent:—

1. In a folding bed, the combination of a pair of supporting members, a bed frame, a pair of links pivoted to the bed frame and to one of said supporting members on the same side, and a spring device connected to one of said links and to the bed frame, said spring device being arranged to be compressed when the bed is extended, and to expand when the bed frame is elevated. 110

2. In a folding bed, the combination of a pair of supporting members, a bed frame pivotally supported by one of said members, a pair of links connecting the side bars of the bed frame with the other supporting member, one of said links being shorter than the other, and a spring device connected to the longer of said links and to the bed frame, said spring device being arranged to be compressed when the bed is extended, and to expand when the bed is folded. 120

3. In a folding bed, the combination of a head board and a foot board, supplemental side frames connected to the head board, a 130

bed frame pivotally supported within the said side frames, a pair of links connecting the bed frame to the foot board one of said links being shorter than the other, a spring device connected to the longer of said links near its pivotal connection with the bed frame, said spring device being pivotally connected to the bed frame near the foot board end of said frame and serving to assist in elevating the foot board end of the bed frame.

4. A folding bed comprising a head board and a foot board, supplemental side frames carried by the head board, a bed frame pivoted between said side frames, a pair of links pivotally connected to the bed frame approximately midway between the ends thereof, one of said links being connected to the foot board near the lower end thereof and the other being connected to the foot board approximately at the level of the pivotal connection between the bed frame and the head board, a spring device connected to the link which extends from the bed frame to the lower end of the foot board, the other end of said spring device being connected to the end of the bed frame near the foot board, whereby said spring will be compressed when the bed frame is lowered and will assist in raising the foot board end of the said bed frame.

5. A folding bed comprising a foot board, a head board, a bed frame pivotally supported by the head board, a pair of links connecting the bed frame with the foot board, a notched bar carried by the bed frame near the foot board, said notched bar being adapted to engage one of the links connected to the foot board and to the bed frame to hold the bed frame in an inclined position.

6. A folding bed comprising a head board, a foot board, a bed frame pivotally supported by the head board, a foldable frame connecting the foot board with the bed

frame, and a bar forming an adjustable locking connection between the bed frame and the folding frame for adjusting said bed frame to various inclinations.

7. A folding bed comprising a head board, a foot board, a bed frame pivotally supported by the head board, a foldable frame at the foot portion thereof connecting the foot board with the bed frame and means carried by the bed frame and engaging the folding frame for locking the bed frame in an inclined position.

8. A folding bed comprising a head board, a foot board, a bed frame pivotally supported by the head board, a foldable frame connecting the foot board with the bed frame, and an adjustable toothed bar held to the bed frame and engaging the folding frame to hold said bed frame in various positions.

9. A folding bed comprising a head board, a foot board, a bed frame pivotally supported by the head board, a pair of pivoted links connecting the bed frame with the foot board, one of said links being shorter than the other and the shorter link being substantially horizontal when the bed frame is in its normal open horizontal position.

10. A folding bed comprising a pair of supporting members, a bed frame pivotally supported by one of said members, a pair of links pivotally connected at separated points to the bed frame the other ends of said links being pivotally connected at separated points on the other supporting member, one of said links being shorter than the other and said shorter link being substantially horizontal when the bed frame is in a horizontal position.

This specification signed and witnessed this 14th day of June A. D. 1910.
